UNITED STATES PATENT OFFICE

109,028

DESIGN FOR A DIRECTION INDICATING LAMP OR SIMILAR ARTICLE

Ralph H. Sherlock, Berwyn, Ill., assignor to Hubbard Spool Company, Chicago, Ill., a corporation of Illinois

Application January 28, 1938, Serial No. 74,685

Term of patent 7 years

To all whom it may concern:

Be it known that I, Ralph H. Sherlock, a citizen of the United States and a resident of the city of Berwyn, in the county of Cook and State of Illinois, have invented a new, original, and ornamental Design for a Direction Indicating Lamp or Similar Article, of which the following is a specification, reference being had to the accompanying drawing, forming a part thereof.

On the drawing:

I claim:

The ornamental design for a direction indicating lamp or similar article as shown.

RALPH H. SHERLOCK.
